UNITED STATES PATENT OFFICE.

HENRY DOBBIN, OF BOUND BROOK, NEW JERSEY, ASSIGNOR TO THE BOUND BROOK WOOLEN MILLS, OF SAME PLACE.

DESIGN FOR CLOTH.

SPECIFICATION forming part of Design No. 12,817, dated March 21, 1882.

Application filed November 25, 1881. Term of patent 7 years.

To all whom it may concern:

Be it known that I, HENRY DOBBIN, a citizen of the Kingdom of Great Britain, residing in the village of Bound Brook, county of Somerset, State of New Jersey, have invented and produced a new and original Design for Cloths of the kind known as "Fur Beaver," or cloth having a heavy pile or nap, of which the following is a specification, reference being had to the accompanying drawing, forming part thereof.

Heretofore cloths have been ornamented by diagonal lines, either raised above or depressed below the surface of the cloth, all running in one direction, and also by such lines crossing one another at, or nearly at, right angles, and thus producing square, or nearly square, spaces or figures in the entire surface of the cloth.

My design is different from these, and consists in forming in the surface of the cloth parallel diagonal lines, which I will call the "diagonal lines," (shown at *a a a a.*) These lines are separated from each other by a space of the smooth surface of the cloth. At equal distances from each other, and at substantially the same distance apart as that which separates the diagonal lines, I form a series of short lines, which lie parallel with each other and 25 at substantially right angles to the diagonal lines. These lines I will call the "cross-lines," and they are shown at *b b b b.* They are arranged in rows, which rows lie diagonally across the diagonal lines. The several rows 30 are separated from each other by a space of the cloth upon which the diagonal lines alone appear, substantially as wide as is the length of the cross-lines. On each side of the rows of cross-lines I make a straight line, which 35 lies at an angle of about forty-five degrees to both the diagonal lines and the cross-lines.

These I call the "side lines," and they are shown by *c c c c.* All of these lines—*i. e.*, the diagonal, the cross, and the side lines—are preferably so arranged that they all meet at 45 each end of each of the cross-lines; but this is not essential. The cross-lines and the side lines may meet each other at some point between the diagonal lines. The diagonal lines and the cross-lines form numerous square 50 spaces, *d d d d*, in the surface of the cloth; but the cross-lines may run slightly oblique to the diagonal lines instead of at right angles to them, thus forming lozenge-shaped spaces instead of the rectangular squares *d d d d.* All of these 55 lines may be either elevations above or depressions below the surface of the cloth, the optical effect being substantially the same in either case, and the direction of the diagonal and cross lines may be the reverse of that shown 60 in the drawing—*i. e.*, the long diagonal lines, instead of running from the upper right-hand edge of the pattern to the lower left-hand edge, may be vice versa, and the cross-lines will then lie in diametrically the reverse direction from 65 that shown in the drawing.

I claim—

The design for the surface of cloth herein shown and described, the same consisting of separated and substantially equidistant parallel diagonal lines having rows of separated and substantially equidistant and parallel cross-lines running across them, thus forming square or lozenge-shaped spaces, the rows of cross-lines bounded by side lines and separated from each other by a space on which the diagonal lines alone appear, substantially as wide as is the length of the cross-lines.

HENRY DOBBIN.
